US00D884220S

(12) **United States Design Patent** (10) **Patent No.:** **US D884,220 S**
(45) **Date of Patent:** **** May 12, 2020**

(54) **CEILING BAFFLE**

(71) Applicant: **ARMSTRONG WORLD INDUSTRIES, INC.**, Lancaster, PA (US)

(72) Inventor: **James R. Waters**, Lancaster, PA (US)

(73) Assignee: **AWI Licensing LLC**, Wilmington, DE (US)

(**) Term: **15 Years**

(21) Appl. No.: **29/606,749**

(22) Filed: **Jun. 7, 2017**

Related U.S. Application Data

(60) Division of application No. 29/543,425, filed on Oct. 23, 2015, now Pat. No. Des. 789,562, which is a continuation of application No. 29/466,341, filed on Sep. 6, 2013, now Pat. No. Des. 742,551.

(57) **CLAIM**

The ornamental design for a ceiling baffle, as shown and described.

DESCRIPTION

FIG. 1 is a front view of a ceiling baffle according to the new design;

FIG. 2 is a rear view thereof;

FIG. 3 is a top plan view thereof;

FIG. 4 is a bottom plan view thereof;

FIG. 5 is a right end view thereof; and,

FIG. 6 is a left end view thereof.

When installed, the ceiling baffle may be oriented horizontally.

1 Claim, 4 Drawing Sheets
